UNITED STATES PATENT OFFICE.

WALLACE D. KIMBALL, OF NEW YORK, N. Y., AND ARTHUR E. RIDEOUT, OF CHICAGO, ILLINOIS, ASSIGNEES, BY MESNE ASSIGNMENTS, TO NASHUA GUMMED & COATED PAPER COMPANY, OF NASHUA, NEW HAMPSHIRE.

STRIP SERVING AND CUTTING MACHINE.

Application filed January 30, 1918, Serial No. 214,560. Renewed September 20, 1922. Serial No. 529,484.

To all whom it may concern:

Be it known that we, WALLACE D. KIMBALL and ARTHUR E. RIDEOUT, both citizens of the United States, and residents, respectively, of the city, county, and State of New York, and Chicago, county of Cook, and State of Illinois, have invented new and useful Improvements in Strip Serving and Cutting Machines, of which the following is a specification.

This invention relates to apparatus for cutting and feeding gum sealing strips of the character shown in the copending application of A. E. Rideout, Serial No. 220,863 filed March 6, 1918. The sealing strip there described consists of a definite length of gummed paper tape having one edge slit at intervals to a depth of about one-half the width of the strip. The object of the present invention is to provide a machine, more particularly an attachment for an ordinary strip serving machine, which will cut the spaced slits in one edge of the tape as it is fed and delivered by the serving machine.

In the accompanying drawings we have illustrated the invention as applied to a well known machine which automatically, at predetermined intervals without attention by the operator, moistens, cuts off and delivers a fixed length of tape, such as the machine, for example, in Patent No. 1,271,603, granted to Charles G. Mortimer, July 9, 1918. The slitting attachment which is combined with this machine operates in the moment of dwell between the successive advances of the tape to simultaneously produce the spaced slits in one edge of the tape throughout the entire length served at one operation of the serving machine.

This type of machine is shown in the accompanying drawings, and hereinafter described, and in the said drawings

Fig. 1 is a side elevation of the complete machine;

Fig. 2 is a detail of the slitting knife;

Fig. 3 shows a portion of the paper strip prepared by the machine; and

Fig. 4 is a detail view of a modification.

Referring to the drawings, 1 indicates the strip serving machine as a whole, here shown in outline as a casing enclosing the moistening tank and supporting the feed rolls and cutting mechanism. The gearing for oper-

ating the machine is mounted in the bracket 55 2 attached to one side of the machine, the gearing being driven by a belt from a suitable electric motor 3. The gearing comprises one large master gear 4 from which the slitting attachment is arranged to be 65 operated. The slitting attachment comprises a frame consisting of spaced side bars 5 extending horizontally from the rear wall of the serving machine to the paper roll support 6 which is mounted on the supporting table at a sufficient distance from the serving machine to provide a stretch of exposed strip at least equal in length to the piece to be cut off by the serving machine.

Between the roll support and the serving 70 machine the side bars 5 are connected at intervals by cross bars 7 each of which is made up of two pieces. The upper piece is provided on its underside which immediately overlies the lower piece, with a shallow recess 8 somewhat greater than the width of the tape, and attached to the lower edge of the bar, across the top of the recess, is a stationary shear blade 9. The lower piece of the cross bar has its upper 80 surface plane and lies immediately under the upper piece enclosing the bottom of the recess 8 thereby forming a narrow guide slot through which the tape is threaded when the machine is connected up for use. 85

Pivoted on each cross bar 7 at one end is a vertically swinging shear blade 10 arranged to cooperate with the stationary blade to cut the tape lying in the recess of the cross bar. Each shear blade is operated 90 from a horizontal shaft 11 supported in hangers 12 depending from the side bar 5 adjacent the pivots of the shear blades. The shaft 11 is continuously rotated from the serving machine through suitable beveled 95 gears 13 timed to effect one complete rotation of the shaft 11 for each operation of the strip serving machine.

The shear blades are operated from the shaft 11 by means of a series of eccentrics 100 14, one for each blade, each eccentric operating, by direct contact, a vertically reciprocating plunger 15, which engages at its upper end with the lower edge of the swinging shear blade 10 at a point near its pivot 105 whereby the shear blade will be partially closed to cut the tape without excessive movement of the plunger. In order that the

shears will cut only half way across the tape the length of the plungers and the stroke of the eccentrics are proportioned to but partially close the shears on each operation, that 5 is when the eccentric is in its uppermost position the swinging shear blade will be closed to the position indicated in the light, broken lines in Fig. 2.

The gears 13 will be so timed that the 10 shaft 11 comes to rest with the blades open to position shown in heavy, broken lines in Fig. 2, and it will be noted that the cutting edge of the blade drops to a position considerably below the edge of the stationary 15 blade before moving up to cut the tape whereby the eccentric will rotate through about three-quarters of a revolution before the blades come in contact. This period is sufficient for the desired length of tape to 20 be fed by the serving machine.

The machine is designed to allow for the adjustment of the shears along the side bars 5 so as to vary the distance between the cuts. To this end the collars 17 to which the eccentrics 25 are connected are attached to the shaft 11 by means of set screws 21 and the bars 7 are supported from the side angles 5 by clamping screws 22 working in slots (not shown) in the webs of the angles.

30 The serving machine of the above mentioned application is designed to feed tapes of different lengths and in order to adapt the sliding attachment for different lengths of tape, the eccentrics 14 are not fixed to the shaft 11 but are detachably connected thereto by means of locking dogs 16 supported on the eccentrics and each adapted to engage a recess 18 in a collar 17 fixed to the shaft adjacent each eccentric. By this arrangement 35 any number of the knives adjacent the roll support may be rendered inoperative, leaving in action only the necessary number of knives adjacent the serving machine to slit the desired length of tape.

40 The serving machines are also adapted to operate on tapes of different width. As the tape is usually slit to its middle point the slitting attachment will operate on different widths of tape by arranging the shears to 45 close only to the middle point, as shown in Fig. 2, and providing adjustable edge guides 19 for the tape at each recess 8 for maintaining the edges of the tape equally spaced from the edges of the recess. If desired, 50 however, the degree to which the shear blade is closed may be varied by providing an operating plunger 15^a, such as shown in Fig. 4, composed of telescoping parts having a suitable locking connection, such as the 55 set screw 20 whereby the length of the rod may be varied.

One important advantage of the present machine is the arrangement of the shears so as not to cut through the paper. The slit 60 in the edge of the tape might be produced

by a short shear blade extending only to the middle of the tape. It has been found, however, that with this arrangement the end of the shear blade in passing through the tape produces a burr or raised edge at the 70 end of the cut which is apt to catch on the tape guides and cause the tape to tear as it is advanced by the feed rolls of the serving machine. By having the shear blade longer than the cut a short cut is produced which 75 has no upstanding edges to obstruct the feed movement.

It is obvious, of course, that the details of the machine may be variously modified, for instance, cams may be used in place of the 80 eccentrics to effect the operation of the shears. Other changes may also be made without departing from the spirit of the invention or the scope of the appended claims.

We claim:

1. In a machine of the class described, the combination of means to advance, moisten and cut off a predetermined length of gummed paper from a roll, a support for said roll and means operating upon the tape 90 before it reaches said advancing and moistening means for making a plurality of cuts at spaced intervals in the length to be cut off.

2. In a machine of the class described, 95 the combination of means for moistening, advancing and cutting off a predetermined length of gummed tape from a roll thereof, a support for said roll and means arranged between said roll support and said moistening, advancing and cutting means for cutting a plurality of slits in one edge of the length of tape between the roll and said other means.

3. In a machine of the class described, the 105 combination of intermittently operated means to advance, moisten and cut off a predetermined length of gummed tape from a roll, a support for said roll and means operating upon the tape before it reaches said 110 advancing and moistening means for making a plurality of cuts at spaced intervals in the length to be cut off, said last-named means being operated during the period of dwell between operations of said first-mentioned 115 means.

4. In a machine of the class described, the combination of means to periodically advance a strip and cut off a length therefrom and means operating in the intervals of 120 dwell between said periodical advances for simultaneously making a plurality of transverse cuts at spaced intervals in one edge of said strip, said means comprising a plurality of shears supported in spaced relation, means for guiding the strip between said shears and means for simultaneously operating said shears.

5. In a machine of the class described, the combination with means to advance a strip 130

of sheet material of an edge cutter comprising a pair of shear blades arranged for their edges to close progressively transversely of the strip, means for guiding the strip between said edges and means for operating said shears to close them only part way across the width of the strip before their next opening movement.

6. In a machine for advancing a strip of sheet material means for producing a series of spaced cuts in one edge of the strip to be advanced comprising a plurality of pairs of shear blades having their edges arranged to close transversely of the strip and means for optionally rendering inoperative any desired number of pairs of said blades.

7. In a machine for advancing a strip of sheet material means for producing a series of spaced cuts in one edge of the strip to be advanced comprising a plurality of pairs of shear blades having their edges arranged to close transversely of the strip, and means for operating said shears to close them to a predetermined point only, said pairs of blades being adjustable longitudinally of the strip whereby the distance between cuts may be regulated as desired.

8. In a machine for advancing a strip of

sheet material, an edge cutter comprising a pair of shear blades having their edges arranged to close transversely of the strip to be advanced, means for guiding the strip between said edges, means for operating said shears to close them part way only across the width of the strip, and means to vary the degree of closing of said shears.

9. In a machine for advancing a strip of sheet material, an edge cutter comprising a pair of shear blades having their edges arranged to close transversely of the strip to be advanced, means for operating said shears to close them to a predetermined point only and a guide having adjustable guiding walls whereby strips of different widths may be guided between said shear edges to be slit transversely the same proportional extent of their width.

Signed at New York in the county of New York and State of New York, this 5th day of Dec., 1917. 50

WALLACE D. KIMBALL.
